US00D891411S

(12) **United States Design Patent** (10) **Patent No.:** **US D891,411 S**
(45) **Date of Patent:** **** Jul. 28, 2020**

(54) **MOBILE PHONE**

(71) Applicant: **HUAWEI TECHNOLOGIES CO., LTD.**, Shenzhen (CN)

(72) Inventor: **Zhaozhao Liu**, Shenzhen (CN)

(73) Assignee: **HUAWEI TECHNOLOGIES CO., LTD.**, Shenzhen (CN)

(**) Term: **15 Years**

(21) Appl. No.: **29/662,895**

(22) Filed: **Sep. 10, 2018**

(30) **Foreign Application Priority Data**

Mar. 9, 2018 (CN) 2018 3 0087156

(51) **LOC (12) Cl.** **14-03**

(52) **U.S. Cl.**

USPC ..... **D14/248**; D14/138 C

(58) **Field of Classification Search**

USPC ..... D14/248, 138 G, 138 AD, 138 AB,
D14/138 AA, 138 C

CPC H04M 1/02; H04M 1/0279; H04M 1/0202;
H04M 1/0283; H04M 1/0268

See application file for complete search history.

Primary Examiner — Bridget L Eland

(74) *Attorney, Agent, or Firm* — Kilpatrick Townsend & Stockton LLP

(57) **CLAIM**

The ornamental design for a mobile phone, as shown and described.

DESCRIPTION

FIG. 1 is a front view of a first embodiment of a mobile phone showing my new design;

FIG. 2 is a rear view thereof;

FIG. 3 is a left view thereof;

FIG. 4 is a right side view thereof;

FIG. 5 is a top view thereof;

FIG. 6 is a bottom view thereof;

FIG. 7 is a front view of a second embodiment of a mobile phone showing my new design;

FIG. 8 is a rear view thereof;

FIG. 9 is a left view thereof;

FIG. 10 is a right side view thereof;

FIG. 11 is a top view thereof;

FIG. 12 is a bottom view thereof;

FIG. 13 is a front view of a third embodiment of a mobile phone showing my new design;

FIG. 14 is a rear view thereof;

FIG. 15 is a left view thereof;

FIG. 16 is a right side view thereof;

FIG. 17 is a top view thereof; and,

FIG. 18 is a bottom view thereof.

The broken line showing of portions of the mobile phone in FIGS. 1 through 18 represent environmental structure and form no part of the claimed design.

1 Claim, 18 Drawing Sheets
